UNITED STATES PATENT OFFICE

FRED J. BLAKESLEE, OF GRAND RAPIDS, MICHIGAN, ASSIGNOR TO AMERICAN SEATING COMPANY, OF GRAND RAPIDS, MICHIGAN, A CORPORATION OF NEW JERSEY

FURNITURE CONSTRUCTION

Application filed November 9, 1929. Serial No. 405,896.

The present invention relates to furniture construction, particularly theatre chairs and the like; and its object is, generally, to provide an improved construction of that character; and more particularly, to provide a construction wherein a pair of members are united directly with each other through an intervening member; and further, to provide such a construction wherein said pair of members are of weldable metal; and further, to provide a pair of adjacent chairs having a common support between them and back or seat portions united directly with each other through openings in the support.

This and any other and more specific objects hereinafter appearing are attained by, and the invention finds preferable embodiment in, the construction hereinafter particularly described in the body of this specification and illustrated by the accompanying drawing, in which:

Figure 1 is a sectional view of a theatre chair construction taken on a horizontal plane corresponding to line 1—1 of Figures 2, 3 and 4;

Figure 2 is an elevational view of a side member of a chair back;

Figure 3 is a view in perspective of the upper portion of a supporting member for the backs and seats of adjacent chairs;

Figure 4 is an elevational front view of an adjacent pair of such side members and a sectional view of such a supporting member taken on line 4—4 of Figure 1; and

Figure 5 is a transverse sectional view of said parts taken on line 1—1 of Figures 2, 3 and 4.

In the embodiment of the invention illustrated by the drawing, a theatre chair construction is shown comprising a row of chairs disposed side by side and having upwardly extending supporting members 1 with chair seats and chair backs on their opposite sides, each member 1 thus sustaining the seats and the backs of the chairs on its opposite sides and being common to both the adjacent chairs.

These supporting members 1 are usually metal castings and have in their opposite sides upwardly extending grooves 2 with rear walls 3. Openings 4 extend through these

members 1 between the bottoms of the opposite grooves. The back of each chair comprises a body 5 of wood or the like and opposite side members 6 preferably of springable and weldable sheet metal. These side members have flanges 7 mounted on the body 5 of the chair back as by screws 8 extending through slots 9 in said flanges and threaded in said body, these side members having also flanges 10 mounted in the grooves 2. These flanges 10 have offset portions 11, such portions of a pair of adjacent side members 6, 6 approaching each other and extending into the openings 4 from the opposite ends thereof respectively.

The adjacent surfaces of the offset portions 11 are in mutual contact and are united directly with each other through the openings 4, as by spot welding.

It will be seen that by this construction wooden or cast metal members 1 are readily combined with chair members 6 of weldable metal.

The rear flanges 7 being of springable metal inclined rearwardly and inwardly and being spaced at 12 from the rear walls 3 of the grooves 2, the chair back is adapted to yield rearwardly under pressure by the occupant of the chair.

An arm rest or chair arm is indicated at 13, and chair back upholstery sheet is shown at 14 and its packing at 15.

The invention being intended to be pointed out in the claims, is not to be limited to or by details of construction of any particular embodiment thereof illustrated by the drawings or hereinbefore described.

I claim:

1. A construction comprising: a member having an opening therethrough; a pair of separate members on the opposite sides respectively of the first-mentioned member and having offset portions respectively extending into said opening and united directly within the same.

2. A construction comprising: a member having an opening therethrough; a pair of sheet metal members on the opposite sides respectively of the first-mentioned member and having mutually approaching offset por-

tions extending into said opening and united directly within the same.

3. In chair construction: a pair of chairs disposed side by side and having between them a support common to both chairs having an opening therethrough; separate backs for the chairs respectively comprising side members adjacent the support at least one of said side members have an offset portion 10 extending into said opening and united directly with the other one of said side members through said opening.

4. In chair construction: a pair of chairs disposed side by side and having between them a cast-metal support common to both chairs having an opening therethrough, the chairs comprising mutually adjacent sheet-metal members respectively having mutually approaching offset portions extending into 20 the opening and united directly within the same.

5. In a chair of the character described: a pair of supports having in their inner sides upwardly extending grooves with rear walls; 25 a back for the chair comprising a body and upwardly extending springable metallic side members having flanges mounted in the grooves and other flanges mounted on said body and inclined rearwardly-inwardly in spaced relation to said rear walls.

6. In chair construction: a plurality of chairs disposed side by side and having between adjacent chairs supports common thereto having in their opposite sides upwardly extending grooves and openings extending through the supports between the bottoms of the grooves; backs for the chairs each comprising a body and upwardly extending sheet metal side members having 40 flanges with offset portions directly united through said openings and other flanges mounted on said bodies and inclined rearwardly-inwardly.

7. A construction comprising: a member 45 having an opening therethrough; a pair of separate metallic members on the opposite sides respectively of the first-mentioned member at least one of said metallic members having an offset portion extending into said 50 opening and welded to the other one of said metallic members through said opening.

8. A construction comprising: a member having an opening therethrough; a pair of separate members on the opposite sides respectively of the first-mentioned member, one of said pair having an offset portion extending into said opening and having at its extremity a flat face parallel with the other one of said pair, said other one of said pair 60 and said flat face being united directly with each other through said opening.

9. A construction comprising: a member having an opening therethrough; a pair of separate members on the opposite sides respectively of the first-mentioned member,

one of said pair having an offset portion extending into said opening and having at its extremity a flat face parallel with the other one of said pair, said other one of said pair and said flat face being united directly with 70 each other through said opening, said member having the offset portion having also a shoulder engaging the adjacent side of the first-mentioned member in the united position of said pair.

In testimony whereof I have hereunto set my hand at Grand Rapids, Michigan, this 6th day of November, 1929.

FRED J. BLAKESLEE.
